Primary Examiner — Dana L Meyrow*(74) Attorney, Agent, or Firm* — Greer Burns & Crain, Ltd.; Peter Klobuchar(57) **CLAIM**

I claim the ornamental design for a bottle, as shown and described.

DESCRIPTION

FIG. 1 is a perspective view of the design for a bottle; FIG. 2 is a side elevation view of the design for a bottle; and,

FIG. 3 is a top plan view of the design for a bottle. Features shown in broken lines in the drawings are not part of the claim.
